UNITED STATES PATENT OFFICE.

AXEL S. VOGT, OF ALTOONA, PENNSYLVANIA.

AXLE-BOX.

SPECIFICATION forming part of Letters Patent No. 352,592, dated November 16, 1886.

Application filed May 4, 1886. Serial No. 201,043. (No model.)

To all whom it may concern:

Be it known that I, AXEL S. VOGT, of Altoona, Blair county, State of Pennsylvania, have invented a new and useful Improvement 5 in Axle-Boxes, of which the following is a true and exact description, due reference being had to the accompanying drawings, which form a part of this specification.

My invention has especial reference to axle-boxes for railway-car trucks, which it is necessary to close tightly to prevent the entrance of dust and grit, and which must also be easily opened for examination and the renewal of the oil and packing.

15 The object of my invention is to provide a door or lid which when closed will press firmly against its seat, and completely close the axle-box, and which when opened will remain open until forcibly closed; and it consists in the devices hereinafter fully described, and which are illustrated in what I believe to be their best form by the accompanying drawings, of which—

Figure 1 is a central sectional elevation 25 through the axle-box and its lid; Fig. 2, a side elevation of the same; Fig. 3, a front view of that part of the hinge which is cast with the axle-box; Fig. 4, a perspective view of the same on the section $x-x$ of Fig. 3. Fig. 5 is a 30 back view of the hinge put together; Figs. 6 and 7, side and front views of the compressing-arm. Fig. 8 is a diagram illustrating the action of my device when in use.

A is the axle-box, having the rim $a-a$ around 35 its open end made flat and level.

B is the hinge lug or section, secured to or cast with the box. The form and construction of this hinge-lug is fully shown in Figs. 3, 4, and 5. It is perforated longitudinally for the 40 reception of the hinge-pin, as shown in Fig. 5, and at b , Fig. 4.

In the front of the hinge-lug B is an open slot, b^2 , and at the top of the slot, and near the top of the lug, is a recess, b' , (see Figs. 3 and 4,) forming a bearing for the compressing-arm E, Figs. 6 and 7.

b^3 is a projection on the back of lug B.

C is the lid which closes the opening in the 45 box A. If desired, it may have a rim of soft metal cast into a recess in its fitting-face which rests upon the rim a of the box.

c' are lugs perforated for the reception of

the hinge-pin, and adapted to register with the lug B, as shown in Fig. 5.

c^2 is a curved hood which projects over the 55 top of the hinge, covering the recess b' , and terminating in a shoulder, c^3 , adapted to rest against the shoulder b^3 when the lid is open.

c^3 is a hollow box or pocket cast in the lid C and open at the top.

60 D is a spiral spring contained in the pocket c^3 . The axial line of the pocket must be such as will when the lid is closed form a very obtuse angle, such as J K L, Fig. 8, with the compressing-arm E, hereinafter described, 65 which angle will have its apex pointing toward the box.

E is the compressing-arm, having at its top, circular projecting arms $e-e$, which are adapted to rest in the horizontal recess b' , and at its 70 bottom a plug, e' , adapted to enter the spring D, and a collar, e^2 , to rest against the end of the spring. This collar e^2 should be large enough to nearly fill the opening c^3 , though capable of moving freely in it. The shaft e^3 75 of the arm E is of a size which permits it to move freely in the slot b^2 .

F is the hinge-pin; f, an elastic washer.

f' is a key to retain the pin F in place.

To secure the lid to its hinge, the compressing-arm E is first placed in its bearings b' and the spring D is placed in its box c^3 . The end e' of the arm E is then inserted in the end of the spring and the lid C then pressed upward into its proper position, when the perforations 85 of the lugs B and c' will be in line and the pin F may then be inserted. The upper or bearing surface of the recess b' should be made to project forward sufficiently to prevent the end e of the compressing-arm E from slipping out; 90 but as an additional protection I provide the projecting hood c^2 , which will prevent the arm E from slipping out of place, and also serves as a shield to the hinge mechanism.

The operation of my device will be readily 95 understood, and is illustrated in the diagram, Fig. 8.

When the lid C is closed, as shown in Figs. 1 and 2, the face of the lid is in the line G H, Fig. 8, and the axial line of the arm E is represented by the line J K, while the line K L indicates the axial line or line of pressure of the spring D, the points G and J being, respectively, the fixed centers of the hinge and

of the bearings upon which the arm E turns. As will be seen, the spring D being under compression, its power is exerted in this position to keep the lid C tightly pressed down upon its seat, and the lid can only be opened by further compressing the spring.

G H' and G H² are two intermediate positions of the lid-face while being opened, the corresponding axial lines of the arm E being shown by the lines J K' and J K² and of the spring D by the lines K' L' and K² L², while G H³ shows the face of the fully-opened lid, the arm E being then indicated by J K³ and the spring by K³ L³. As indicated by this diagram, the angle J K L becomes more obtuse as the lid is forced open until, after becoming a straight line, the apex of the angle reappears in the reverse direction and the force of the spring is then exerted to open the lid C, the shoulders b³ and c⁵ serving as stops to prevent the lid from being too widely opened. The pressure of the spring D is of course sustained by the hinge-pin F, which is thus tightly clamped between the lug D and the lugs c' c'. The elastic washer f, by drawing the key f' tightly against the lug c', also aids to prevent the pin being shaken loose by the motion of the car.

While, as I have stated, I believe the construction shown and above described in detail to be the best form in which my invention can be applied, it can be varied in many particulars without departure from my invention. Thus the pocket c³ may be dispensed with and the spring secured in some other way. The spring itself need not necessarily be a spiral, for any form of spring may be used, care being taken that it shall transmit its pressure to the lid C in substantially the direction shown in the drawings, and, obviously, the form of the metal compressing-arm E may be changed in many ways. The arms e, for instance, may be dispensed with, and the arm E provided with a semi-cylindrical or spherical head, a fitting-socket being provided in its abutting place on the box in place of the horizontal socket b', and of course other stop devices may be substituted for the shoulders b³ and c⁵, nor need the abutting place be situated on the hinge-lug. A separate lug may be provided in another place for this purpose.

The essential features of my invention consist of the arrangement of the spring and the compressing-arm with respect to the hinge and lid-face, so that an elastic toggle-joint will be formed to keep the lid closed, and closed

and opened substantially in the way indicated.

Having now described my invention, what I claim as new, and desire to secure by Letters 60 Patent, is—

1. In an axle-box having a hinged lid, substantially as described, the combination of a compressing-arm journaled or pivoted on the box, with a spring abutting against the lid and transmitting its pressure thereto in one direction and through the compressing-arm to the box in the other direction, substantially as and for the purpose shown and described.

2. In an axle-box having a hinged lid, substantially as described, the combination of the compressing-arm pivoted on the box, the spring abutting against the lid, and the lid-hinge arranged in relation to the arm-pivot and line of thrust of the spring, substantially as shown and described, so that one component of the pressure between the spring and the compressing-arm is directed toward the fitting-face of the lid when it is closed and away from said face when it is wide open.

3. In an axle-box having a hinged lid, substantially as described, the combination of the socket b', situated on the box, the pocket c', formed in the lid, the spiral spring D, and the compressing-arm E, pivoted at one end in the socket b', and having its other end inclosed in the pocket c' and resting against the spring D, all substantially as and for the purpose specified.

4. In an axle-box having a hinged lid, the combination of the socket b', situated on the box, the lid C, having a spring secured thereto, substantially as and for the purpose specified, and having a hood, c², extending over and covering the socket b', and the compressing-arm pivoted in the socket b' and bearing against the spring, all substantially as and for the purpose specified.

5. In an axle-box having a hinged lid, the combination of the hinge-lug B, having a bearing or socket, b', and a slot, b², extending downward from the bottom of said socket, the door or lid C, having hinge-lugs c' c', a box or pocket, c³, and hood c², extending over the open socket b', the spring D, and compressing-arm E, having arms e e, all substantially as and for the purpose specified.
